C. A. Snow, Esq.

UNITED STATES PATENT OFFICE.

ROBERT H. JOHNSON, OF CHATTANOOGA, TENNESSEE.

CUTTING-NIPPERS.

SPECIFICATION forming part of Letters Patent No. 377,759, dated February 14, 1888.

Application filed November 21, 1887. Serial No. 255,826. (No model.)

To all whom it may concern:

Be it known that I, ROBERT H. JOHNSON, a citizen of the United States, residing at Chattanooga, in the county of Hamilton and State 5 of Tennessee, have invented new and useful Improvements in Cutting-Nippers, of which the following is a specification.

My invention relates to improvements in cutting-nippers provided with reversible edges; 10 and it consists in the construction and novel combination of parts, hereinafter described, illustrated in the drawings, and pointed out in the claims hereto appended.

In the accompanying drawings, Figure 1 15 represents a side view of a pair of nippers embodying the invention. Fig. 2 represents a perspective view of one of the double-edged detachable cutter dies or blocks. Fig. 3 represents a perspective view of one of the nip- 20 per-jaws, showing the recess therein whereby the corresponding cutter die is attached to the jaw.

Referring to the drawings by letter, A designates a pair of nippers having the similar 25 jaws, B, and similar handles, C. When the nippers are closed, the upper flat surfaces, b b, of the jaws are aligned with each other and with the upper or outer flat surfaces of the cutter dies, hereinafter described.

D D are the cutter dies, each of which has 30 a central inclined portion or web, d, and similar edge portions, E, on each side of the web, the faces e of which edge portions are parallel to each other and inclined to the opposite 35 parallel faces, d', of the web. The face e of each edge portion is connected to the web on the unprotected sides thereof by the outwardly inclined surfaces F f, the former of which makes a more acute angle with the face of the 40 corresponding edge portion, the said angle G constituting the cutting-edge of the die.

The inclined surfaces E f of one edge portion of a cutter-die are respectively on opposite sides of said die to those on which the 45 corresponding surfaces of the other edge portion are, as shown in Fig. 2, so that when the die is reversed the lower cutting-edge G will occupy the same position as the upper cutting-edge did before reversal.

Each jaw B is provided with a transverse 50 dovetailed recess, H, into which can be slid and fitted either of the edge portions of the corresponding cutter-die with its cutting-edge G outward. From the outer edge of said recess the surface h of the jaw is inclined inward a sufficient distance to lie closely against the adjacent face d' of the web, and then inclined sufficiently outward, as at h', to lie closely against the adjacent inclined surface f of the outer edge portion of the cutter-die. It is evident 55 from the above that as the opposite sides of the cutter-die are similar they will fit equally closely in the dovetailed recess H and against the surfaces h h', and will always have the cutting-edge not in the recess facing inwardly, 60 as that in said recess must necessarily face outwardly.

Having thus described my invention, I claim—

1. The combination, with the nippers having 70 similar transverse dovetailed recesses, H, at corresponding points in its jaws, of the cutter-dies D, each having a web, and similar opposite edge portions, E, provided with cutting-edges G, facing in opposite direction, either of 75 which edge portions can be slid and fitted into the corresponding recess H, with its cutting-edge outward, substantially as specified.

2. The combination, with the nippers having 80 the handles C and similar jaws, B, each provided with the dovetailed transverse recess H and inclined surfaces h h', of the cutter-dies D, each provided with a web, d, having parallel opposite faces, d', and the edge portions, E, 85 each having the face e, inclined surfaces F f, and cutting-edge G, the cutting-edges of the two edge portions facing in opposite directions, substantially as specified.

In testimony that I claim the foregoing as my own I have hereto affixed my signature in 90 presence of two witnesses.

ROBERT H. JOHNSON.
